WINDOW CONSTRUCTION

Schley E. Smith, Rock Island, Ill.

Application September 16, 1935, Serial No. 40,803

1 Claim. (Cl. 189—64)

This invention relates to window constructions, and has for the primary object the provision of a device of this character which embodies a novel construction of metallic window frame and sliding sashes therefor to which either glass or screen panels may be readily adapted to or removed from when desired.

With these and other objects in view, this invention consists in certain novel features of construction, combination and arrangement of parts to be hereinafter more fully described and claimed.

For a complete understanding of my invention, reference is to be had to the following description and accompanying drawings, in which—

Figure 1 is a front elevation illustrating a window frame construction and sliding sashes therefor and constructed in accordance with my invention.

Figure 2 is a sectional view taken on the line 2—2 of Figure 1.

Figure 3 is a sectional view taken on the line 3—3 of Figure 1.

Figure 4 is a fragmentary perspective view illustrating one of the vertical portions of the window frame.

Figure 5 is a fragmentary perspective view showing one of the vertical and horizontal portions of the sash.

Figure 6 is a perspective view illustrating a cushion block.

Figure 7 is a fragmentary perspective view showing a panel holder.

Figure 8 is a fragmentary side elevation showing a part of the sash.

Figure 9 is a fragmentary side elevation showing the application of the window panel holder connected to the sash.

Figure 10 is a detail sectional view taken on the line 10—10 of Figure 9.

Referring in detail to the drawings, the numeral 1 indicates a metallic window frame including vertical members 2 and horizontal strips 3. The strips 3 are welded or otherwise secured to the ends of the vertical members 2 for holding the latter in spaced relation. Each member 2 is of channel iron construction, as shown in Figure 4, consisting of a bight portion 4, arm portions 5 bent to form channel-shaped guides 6. The bight portion 4 is provided with apertures 1 to receive fasteners for securing the frame 1 to a building. The channeled guides 6 slidably support window sashes 8.

Each sash 8 comprises vertical and horizontal rails 9 and 10. The rails 9 and 10 are welded

or otherwise secured together. The rails 9 are of substantially rectangular shape in cross section having the front walls thereof cutaway to form entrances 11 and are also provided with horizontally arranged slots 12 communicative with the entrances 11. The walls of the slots 12 form mountings for cushion blocks 13 each provided in opposite faces thereof with grooves 14 to receive opposed walls of the slots 12. The cushion blocks extend into the entrances 11 and also project inwardly of the rails 9 as well as outwardly of said rails. The rails 9 are slidably received in the channeled guides 6, as shown in Figure 3, with the blocks having frictional contact with the walls of the guides. The blocks 13 will maintain the sashes 8 in their adjusted positions relative to the window frame 1 and will prevent the sashes from rattling in the frame and will permit the sashes to be manually slid upwardly or downwardly as desired in the frame 1.

Each rail 10 consists of an angle iron portion 15 and a box-like portion 16 in cross section. The wall 17 of the portion 16 is disposed at a desired inclination so that the rail 10 of the lower sash will snugly fit the rail 10 of the upper sash when said sashes are in frame-closing position. The wall 18 of each rail 10 has slots 19 to receive fasteners 20. The wall 21 of each rail 15 forms an abutment or stop.

The fasteners 20 are carried by panel frames 22 each of substantially rectangular shape and which support either a glass or screen panel. Each panel frame 22 has secured to the vertical rungs thereof channel members 23 adapted to extend into the entrances 11 of the sashes 8. The horizontal rungs of each panel frame abut the walls 18 and 21 of the rail 15. The fasteners 20 are journaled to the horizontal rungs of the panel frames 22 and each include a stem 24 provided with a finger piece 25 at one end and an elongated head 26 at the opposite end. The heads 26 are capable of moving through the slots of the horizontal rails when positioned in parallelism therewith and when turned at right angles thereto will efficiently secure the panel frames in position in the sashes 8.

A construction of the character described may have used in conjunction therewith any suitable type of weather stripping so that atmospheric conditions will be excluded and also a construction of this kind will be durable, easily assembled and operated and may be manufactured and sold at a low cost.

Having described the invention, I claim:

A window construction comprising channel guides, sash frames including vertical and horizontal rungs and having the vertical rungs thereof slidably supported by said guides, cushion friction blocks carried by the vertical rungs and engaging walls of the guides, said vertical rungs

having entrances, panel supporting frames abutting the sash frames, and channel guides formed on the panel supporting frames and extending into the entrances of the vertical rungs of the sash frames.

SCHLEY E. SMITH.
